UNITED STATES PATENT OFFICE

160,365

CONTROL VALVE FOR GAS BURNERS

Isaac Vernon Brumbaugh, Clayton, Mo.

Application June 25, 1948, Serial No. 147,182

Term of patent 14 years

(Cl. D78—1)

To all whom it may concern:

Be it known that I, Isaac Vernon Brumbaugh, a citizen of the United States, residing at Clayton, in the county of St. Louis and State of Missouri, have invented a new, original, and ornamental Design for a Control Valve for Gas Burners, of which the following is a specification, reference being had to the accompanying drawing, forming a part hereof.

Fig. 1 is a perspective view of a control valve for gas burners embodying my new design, with the handle turned to the "on" position.

Fig. 2 is a perspective view of the valve from a different angle with the handle turned to the "off" position;

Fig. 3 is a perspective view of the valve with the handle in the "on" position showing the sides opposite those shown in Figs. 1 and 2.

The dominant features of my design reside in the portions shown in full lines.

I claim:

The ornamental design for a control valve for gas burners, as shown and described.

ISAAC VERNON BRUMBAUGH.
